UNITED STATES PATENT OFFICE.

CHARLES W. RUSSELL, OF LOUISVILLE, KENTUCKY.

DESIGN FOR A COMMODE-CHAIR.

SPECIFICATION forming part of Design No. 29,992, dated January 10, 1899.

Application filed July 11, 1898. Serial No. 685,650. Term of patent 3½ years.

To all whom it may concern:

Be it known that I, CHARLES W. RUSSELL, a citizen of the United States, residing at Louisville, in the county of Jefferson and State of Kentucky, have invented and produced a new and original Design for Commode-Chairs, of which the following is a specification, reference being had to the accompanying drawing, forming part thereof.

The principal features of my invention are short curved supporting - arms and long curved back-supports, forming the legs and back of a chair, a quadrilateral seat, and a quadrilateral box 1, having ogee-shaped sides and an overhanging ledge immediately underneath the seat. 15

Having thus described my invention, what I claim as new, and desire to secure by Letters Patent, is—

The design for a commode-chair, as herein 20 shown and described.

CHARLES W. RUSSELL.
